UNITED STATES PATENT OFFICE.

ALBERT HITZERT, OF SAGINAW, MICHIGAN.

ATTACHMENT FOR SHIPPING-PACKAGES.

1,139,523.

Specification of Letters Patent. Patented May 18, 1915.

Application filed July 5, 1910. Serial No. 570,509.

To all whom it may concern:

Be it known that I, ALBERT HITZERT, a citizen of the United States, residing at Saginaw, in the county of Saginaw and 5 State of Michigan, have invented certain new and useful Improvements in Attachments for Shipping-Packages; and I do hereby declare the following to be a full, 10 clear, and exact description of the invention, such as will enable others skilled in the art to which it appertains to make and use the same.

This invention is an improvement in attachments for shipping packages and relates 15 more particularly to devices adapted to be attached to packages of merchandise, such as crackers and the like, whereby the shipping package is easily and quickly converted into a dispensing package.

20 It has been customary heretofore in the retailing of crackers and like articles to transfer them from the original shipping package or box to a dispensing case or other suitable receptacle, in which is provided a 25 downwardly opening door or other suitable device whereby the lower part of the dispensing case is provided with a tray or hopper onto which the crackers spread and from which they are taken up by a hand 30 scoop.

My present improvement provides for the retailing of the goods from the original shipping package by attaching to the shipping package an inexpensive device comprising 35 a tray and cover therefor, of such construction as to be easily and quickly applied to the package. The device also comprises means for holding the scoop when the cover is down, and means for exposing the handle 40 of the scoop when the scoop is left in the package.

My improvement is illustrated in the accompanying drawings, in which—

Figure 1 is a perspective view of the device attached to a shipping package; Fig. 2 is a perspective view showing the method of cutting the side of the shipping package in order to apply my improvement; Fig. 3 is a vertical sectional detail, the section being 50 taken on the line $x-x$ of Fig. 1; and Fig. 4 is an enlarged perspective view of the attachment.

As is clearly shown in the drawings, the device consists in an inclined tray 1, bent 55 up at its ends to form sides 2, and having a hinge cover 3.

The top rear portions of the sides 2 are notched as at 4, and the lower edges are provided with downwardly extending projections 5. The notches 4 and projections 5 60 form a means by which the attachment is held in place on the shipping package 6. To apply the attachment to a shipping package, one side of the package is cut through horizontally as at 6^a, when the package is 65 opened, and vertically as at 6^b so that the flap 6^c thus formed may be bent outwardly as indicated at 6^c in Fig. 2. Upwardly extending slits 6^d are also formed in the side 70 of the package.

The distance between the slits 6^d, 6^d is made the same as the distance between the sides 2, 2 of the attachment so that the rear edges 2^a of the sides may be inserted in the slits 6^d, 6^d of the package. The notches 75 4, 4 are received in the slots 6^d, 6^d so that the upward projections 2^b, 2^b engage behind the front of the package and the projections 5 rest against the bottom edge of the package as indicated in Fig. 3, thereby holding 80 the attachment in place on the package but permitting its easy detachment.

The cover 3 is hinged to the sides 2, 2, the rear edge 3^a of the cover forming a hinge by being rolled around a wire 7. In order 85 to keep the hinge 3^a tight against the face of the package, thereby preventing the entrance of dust, the hinge 3^a is yieldingly pressed rearwardly against the package, the means by which this is accomplished being 90 illustrated in Figs. 1 and 4, where 7^a, 7^a are looped portions formed in the wires 7, the intermediate portion of which is rolled into and fits loosely into the upper edge 2^c of each of the sides 2. The spring 7^a is secured at the 95 front edge to the tray 1 by clamps 1^a formed by bending over the metal of the tray 1. The spring members 7^a are so bent that they tend to thrust the wires rearwardly through the rolled members 2^c and thereby keep the 100 wire 7 and the hinge 3^a forced back against the front face of the package, at the same time drawing the members 2^b forward against the inner face of the package, thereby holding the cover 3 tightly against 105 the package. The pressure thus brought upon the hinge 3^a also serves by frictional contact with the front of the package to retain the cover 3 in its raised position without the aid of other fastenings.

The edges of the cover are bent up as at 3^c, to serve as a reinforcement or stiffener 110

for the cover and also to form a ledge so that when the cover is closed, the scoop by which the material is handled, may be laid on the cover. When it is desired to leave the scoop in the package, the handle of the scoop may be exposed through the cover 3 by leaving it in the opening 3^a formed for that purpose in the cover.

The means by which the tray 1 is secured 10 to the flap 6^c of the package is important. This means consists in forming the tray 1 with a slit 1^b (Fig. 3) and inserting in the slit the outer free end of the flap 6^c, so that the inner part of the flap forms a part of the 15 tray surface. This construction not only enables the attachment to be made lighter than would be the case if the entire bottom of the tray were made solid, but also enables the user to readily adapt a single attachment to packages containing a variety 20 of materials.

Different materials such as crackers, 25 cookies and the like, spread with different degrees of facility over the tray and for a given sized tray, pile up at different heights and require openings of different heights in their respective packages. The slit 1^b in the tray 1 will receive with equal facility either a high flap 6^c or a low one, the high 30 flap merely passing farther through the slit and under the tray, as shown in Fig. 3. Consequently the vertical height of the opening in the box may be made to suit the flowing properties of the material in the box 35 and the attachment may be equally well applied whether the flap 6^c be wide or narrow, it only being essential that the flap shall be received in the slit 1^b and take under the tray 1.

40 Having disclosed my invention, what I

claim and desire to secure by Letters Patent, is:

1. A dispensing attachment for shipping packages, comprising an inclined tray having upwardly and rearwardly projecting 45 sides, a cover hinged to the top edges of said sides, spring members slidably mounted on said sides and adapted to yieldingly press the hinged edge of said cover rearwardly against the side of said package, and means 50 for detachably securing said tray sides to said package.

2. A dispensing attachment for shipping packages, comprising an inclined tray formed with upwardly and rearwardly projecting sides; a cover hinged to the top edges of said sides, said cover provided with means whereby its hinged edge is yieldingly pressed rearwardly against the side of said 55 package, and means for detachably securing 60 said tray sides to a shipping package.

3. A dispensing attachment for shipping packages, comprising an inclined tray having upwardly and rearwardly projecting sides, the upper edges of said sides formed 65 with notches adapted to engage the front of the package to hold the upper part of the tray in place, and the lower edges provided with projections adapted to engage the lower edges of the package; a cover hinged to the 70 top edges of said sides, said cover provided with means whereby its hinged edge is yieldingly pressed against the side of said package.

In testimony whereof, I affix my signature 75 in presence of two witnesses.

ALBERT HITZERT.
